UNITED STATES PATENT OFFICE.

LEO F. MILLARD, OF WHITEWATER, WISCONSIN.

HYDROCARBON-GAS BURNER.

960,366.

Specification of Letters Patent. Patented June 7, 1910.

Application filed May 18, 1908. Serial No. 433,521.

To all whom it may concern:

Be it known that I, LEO F. MILLARD, a citizen of the United States, residing at Whitewater, in the county of Walworth and 5 State of Wisconsin, have invented certain new and useful Improvements in Hydro-carbon-Gas Burners; and I do declare the following to be a full, clear, and exact description of the invention, such as will enable others skilled in the art to which it 10 appertains to make and use the same.

My invention relates to hydro-carbon burners, and particularly to portable burners for brazing, soldering or similar pur- 15 poses.

The object of the invention is to provide a device of this character which will be cheap to manufacture, efficient in operation and convenient of transportation.

20 Several features are essential in burners of this type. First the gas coming from the needle valve to the combustion chamber should be thoroughly mixed with the air and the interior of the chamber should 25 be of such construction as to produce a pointed flame. Second the maximum heat which is generated at the front end of the burner should be properly radiated back to the generating tube or retort, and the com- 30 bustion chamber should be so trussed and supported that the front end will not wilt and become shapeless from excessive heat.

All these objects are necessary in a good burner, and it is endeavored herein to pro- 35 duce such a device with such objects.

With these and other objects in view, the invention consists of certain novel features of construction, combination and arrangement of parts, as will be more fully de- 40 scribed and particularly pointed out in the appended claim.

In the drawings, Figure 1 is a side elevation, Fig. 2 is a longitudinal section of the burner, Fig. 3 is a transverse section on the 45 line $\alpha-\alpha$ of Fig. 1.

Referring more especially to the drawings, 1 indicates a suitable stand provided with a clamping device 2, which holds the feed tube 3 in adjusted position. At one end 50 the feed tube supports the usual supply tank 4, provided with the pressure pump 5, as is usual. The opposite end of the fuel tube 3 is connected by an elbow 6 to the generating ring or retort 7, which surrounds and is cast 55 as a part of the combustion chamber 8. The generating ring is better shown in Fig. 3,

where 9 indicates a channel running there-
through, which connects at its upper end
with a generating tube 10, running along the
top of the combustion chamber 8, and con- 60
necting at its inner end with the elbow 11,
supporting and communicating with the
needle valve 12, whose nozzle 13 projects in-
wardly toward the contracted opening 14 in
the rear of the combustion chamber. As is 65
usual the chamber 8 is cylindrical and is
provided with a plurality of air holes 15,
which admit air for proper commingling
with the gas under pressure from the nozzle
13. The interior of the combustion chamber 70
8 is provided with a series of longitudinally
extending ribs or radiating vanes 16, which
project inwardly from the inside of the
chamber toward its center. A single rib is
located between each row of openings 15 and 75
tapers from a point just forward of the gen-
erating ring to the front and rear end re-
spectively. As the front end of the burner
receives the most heat I preferably run the
forward ends of the vane closely adjacent 80
the discharge end of the combustion cham-
ber so that they will properly support this
end of the chamber, and at the same time
pick up the excess heat at this point and
transmit it to the retort 7 and generating 85
tube 10.

Any suitable means may be provided for
initially heating the retort, and as this
forms no part of my invention I have not
illustrated such a device. After the retort 90
has once been heated it is only necessary to
regulate the amount of flame by the provi-
sion of the needle valve, as is well under-
stood by those versed in the art.

From the foregoing description, taken in 95
connection with the accompanying draw-
ings, the construction and operation of the
invention will be readily understood with-
out requiring a more extended explanation.

Various changes in the form, proportion 100
and the minor details of construction may
be resorted to without departing from the
principle or sacrificing any of the advan-
tages of this invention as defined in the ap-
pended claim.

Having thus described my invention what
I claim and desire to secure by Letters Pat-
ent is:-

A one-piece hydro-carbon burner com-
prising a perforated tubular combustion 110
chamber open at both ends, the opening of
the rear end being contracted, a plurality of

laterally spaced longitudinally extending solid ribs, on the inner face of said combustion chamber and tapering from their centers toward their opposite ends to form a maximum heating surface, said ribs terminating nearer the front than the rear end of said chamber, a retort arranged on the exterior of said chamber around its thickened portion and having means at one side for connection with the source of fuel supply, and a generator tube at its other side, said

15 tube extending longitudinally of the combustion chamber and provided with means at its free end for connection with an injector.

In testimony whereof I have hereunto set my hand in presence of two subscribing witnesses.

LEO F. MILLARD.
